UNITED STATES PATENT OFFICE.

HENRY D. CAPITAIN, OF CHICAGO, ILLINOIS.

HAND-BAG FOR PHYSICIANS AND SURGEONS.

1,009,047.

Specification of Letters Patent. Patented Nov. 21, 1911.

Application filed June 12, 1909. Serial No. 501,719.

To all whom it may concern:

Be it known that I, HENRY D. CAPITAIN, a citizen of the United States, residing at Chicago, in the county of Cook and State 5 of Illinois, have invented certain new and useful Improvements in Hand-Bags for Physicians and Surgeons, of which the following is a full, clear, and exact specification.

10 This invention relates to that class of hand bags for physicians and surgeons adapted to carry not only the surgical instruments which the surgeon is liable to need while visiting his various patients, but also a 15 limited quantity of antiseptics or other medicinal supplies, bandages, etc., and it has especial reference to that class of these hand bags provided with means whereby the surgical instruments may be sterilized and 20 retained in the sterilizing compartment free from contamination by the other articles which the surgeon or physician may see fit to deposit in the bag.

The quantity of material and instruments 25 which the surgeon or physician is liable to require varies, of course, from time to time with the character of the case in which he happens to be engaged, and to the end that the bag may not be unduly large at 30 times when only a small quantity of instruments or material is to be carried, and yet sufficiently large at other times to accommodate the maximum amount, the invention has for its primary object to provide an 35 improved and efficient form of surgeon's or physician's hand bag containing a sterilizing compartment which shall be expandable to accommodate additional material or articles.

Another object of the invention is to provide 40 an article of the described character which shall have both an expandible outer case or bag, and an expandible sterilizing compartment, so that the sterilizing compartment may be expanded to accommodate 45 the varying quantity or number of instruments, and the outer case or bag will expand proportionately, or the bag alone may be expanded independently of the sterilizing compartment to allow for the introduction 50 of a varying quantity of material placed in the bag outside of the sterilizing compartment without expanding the sterilizing compartment.

With these ends in view, the invention 55 consists in certain features of novelty in the construction, combination and arrangement

of parts by which the said objects, and certain other objects hereinafter appearing are accomplished, all as fully shown in the accompanying drawings, described in the following specification, and particularly pointed out in the appended claim.

In the said drawings—Figure 1 is a vertical, longitudinal section of a surgeon's or physician's hand bag embodying this invention. Fig. 2 is a cross section on the line 2—2 of Fig. 1. Figs. 3 and 4 are perspective views of the top and body respectively of the sterilizing compartment.

The outer case or bag proper comprises 70 two main members, a bottom and inner member 1, and an outer and top member 2. The bottom member 1 is in the form of a rectangular box with an open top, while the top member is in the form of an inverted box 75 with an open bottom telescoped with the member 1. The top and outer member 2, however, is preferably formed with hinged lids 3, 4, provided, if desired, with a suitable clasp and lock 5, whereby access to the interior may be readily gained without pulling the telescoped members 1 and 2 apart. When the telescoped members 1, 2, are together, and the bag is in carrying condition, the two members are firmly bound against relative 80 displacement by straps 5^a which pass completely around the bag and are attached to the bottom member only by any suitable means, such as keepers 6, so that the top member may be readily raised and lowered 85 with relation to the bottom member, as the quantity of the material in the bag varies, or may be readily lifted out of telescoped relation with the bottom member when desired. 95

Arranged within the bottom member 1 is a sterilizing compartment which, when in the condition of its smallest capacity, preferably completely fills the bottom member. This sterilizing compartment as clearly shown in 100 Figs. 3 and 4, consists of a box 7 preferably composed of metal, so that its contents may be heated, and to that end the box may be provided with folding legs 8 whereby an alcohol lamp or other heater may be placed 105 thereunder, the box constituting one member of the sterilizing compartment, while the other member is constituted by a lid 9 which fits over and telescopes with the box or body portion 7, and possesses considerable depth, 110 so as to allow for a wide degree of expansion to accommodate a widely varying number

or quantity of instruments or material. It is of course understood that with this same element, which has been called a sterilizing compartment in the specification as a convenient means of designation, may be utilized by the physician in any other way, such, for example, as merely a carrying compartment for his instruments, or as a pan or receptacle in which to disinfect the instruments by any desired method.

Within the body portion 7 of the sterilizing compartment may be arranged a perforated tray 10 upon which the instruments or material may be placed, the tray being provided with handles 11 whereby its contents may be lifted out of the sterilizing compartment without being touched. If desired, a number of bottles 12 may be carried within the sterilizing compartment on top of the tray 10 by means of a removable holder 13 detachably held in the compartment by clips or guides 14 at the ends of the body 7, and having individual clips 15 for the various bottles 12, so that when the sterilizing compartment is to be used for sterilizing the instruments, the tray of bottles may be lifted out temporarily to permit the tray 10 to be removed with the instruments, sufficient play being allowed at the sides of the tray 10 to permit the tray to pass the clips 14 which hold the bottle holder 13.

With an apparatus thus constructed, it will be seen that if the instruments or material to be carried by the physician or surgeon do not exceed the capacity of the sterilizing compartment, all of the same may be placed in said compartment and the entire apparatus collapsed to its minimum size, as shown in cross section in Fig. 2, but should it be desired to carry some articles or material which the surgeon does not wish to place in the sterilizing compartment for fear the instruments might be contaminated thereby, and for the further reason that it is not convenient to open the sterilizing compartment as it may be desired from time to time to put something into the bag or remove something therefrom, such additional articles or material may be placed on top of the sterilizing compartment and the outer casing or bag members 1 and 2 expanded accordingly, and only sufficiently to accommodate such arti-

cles; the bag member 2 being provided with the hinged lids, ready access is afforded to the bag without pulling the telescoped sections entirely apart, which would of course in some cases allow small articles to fall out. Thus it will be seen that two independently expandible compartments are provided, one being the sterilizing compartment and the other being the ordinary carrying compartment constituted by the top of the sterilizing compartment and the side walls and top of the bag member 2. Should it be desired to gain access to the sterilizing compartment without permitting the articles in the ordinary carrying compartment above to fall out, the object may be accomplished by opening the top of the bag and reaching down through the material or articles resting on top of the sterilizing compartment and grasping a handle 16 on said top and then by lifting the bag member 2 by means of said handle, or at least while holding on to the handle, said bag member and its contents together with the lid or top 9 of the sterilizing compartment may be removed from the lower members.

What I claim is:

A physician's and surgeon's hand bag comprising a bottom member, a top member into which the bottom member is slidable, the top member being formed with lids hinged at the sides to uncover the inside of the bottom member, the latter remaining in position within the top member, and a sterilizing compartment formed by two telescopic members disposed within the said bottom member, the top member of the said compartment forming the bottom of a second compartment within the bag, the said sterilizing compartment members being removable from the top and bottom members through the top when the top and bottom members are retained in the same relative position.

In testimony whereof I have signed my name to this specification, in the presence of two subscribing witnesses, on this 10th day of June, A. D. 1909.

HENRY D. CAPITAIN.
